PANEL BOARD FOR INTEGRATED CIRCUIT PACKAGES

James V. Murphy, 28 Ladderlook Road,
Warwick, R.I. 02886

Filed June 18, 1973, Ser. No. 371,232

Term of patent 14 years

Int. Cl. D13—03

U.S. Cl. D26—1 A

FIG. 1

FIG. 2

FIG. 3

FIG. 4

FIG. 1 is a top plan view of one side of a panel board for integrated circuit packages showing my new design, the other side being identical thereto;

FIG. 2 is a side elevational view thereof;

FIG. 3 is a front elevational view thereof; and

FIG. 4 is a rear elevational view thereof.

I claim:

The ornamental design for a panel board for integrated circuit packages, substantially as shown.
